DESIGN FOR A DOLL BUGGY

Martin E. Low, Holland, Mich.

Application October 14, 1944, Serial No. 115,781

Term of patent 14 years

(Cl. D34—15)

To all whom it may concern:

Be it known that I, Martin E. Low, a citizen of the United States, residing at Holland, in the county of Ottawa and State of Michigan, have invented a new, original, and ornamental Design for a Doll Buggy, of which the following is a specification, reference being had to the accompanying drawing, forming a part thereof, in which

the figure is a perspective view of a doll buggy showing my new design, the opposite side is of substantially the same appearance as the side shown.

I claim:

The ornamental design for a doll buggy, substantially as shown and described.

MARTIN E. LOW.
